UNITED STATES PATENT OFFICE

162,902

PAN LINER

Paul Thompson, Wellesley Hills, Mass.

Application April 6, 1950, Serial No. 9,015

Term of patent 14 years

(Cl. D44—1)

To all whom it may concern:

Be it known that I, Paul Thompson, a citizen of the United States, residing at Wellesley Hills, in the county of Norfolk and Commonwealth of Massachusetts, have invented a new, original, and ornamental Design for a Pan Liner, of which the following is a specification, reference being had to the accompanying drawing forming a part thereof, in which:

The figure is a view in perspective of a pan liner showing my new design. The opposite sides thereof are similar to those shown.

I claim:

The ornamental design for a pan liner as shown and described.

PAUL THOMPSON.
